UNITED STATES PATENT OFFICE.

WILLIAM GARDNER, OF TROY, NEW YORK, ASSIGNOR OF ONE-HALF TO
MILTON C. JONES, OF SAME PLACE.

VALVE.

SPECIFICATION forming part of Letters Patent No. 252,094, dated January 10, 1882.

Application filed August 1, 1881. (No model.)

To all whom it may concern:

Be it known that I, WILLIAM GARDNER, of Troy, in the county of Rensselaer and State of New York, have invented certain new and 5 useful Improvements in Valves, of which the following is a specification.

My invention relates to improvements in metallic disk-valves of the class commonly used for steam and water stop-valves; and 10 the object of my improvements is to afford facilities for grinding the disks of such valves to their seats while they are retained by their operating mechanisms; and to this end my invention consists in providing the disk of 15 the valve with a slot or other suitable appliance for receiving a detachable grinding handle or tool, and in providing the screw-stem of the valve with a suitable opening that leads directly to the slot in the disk in such 20 manner that the grinding-tool will be guided into said slot, the opening for receiving such tool being adapted at its outer end to receive a screw-plug or other stopper for the purpose 25 of closing it against any escape of fluid at that point.

In the accompanying drawings, which form part of this specification, and to which reference is herein made, Figure 1 is a longitudinal section of a globe-valve containing my improvements, and Fig. 2 an elevation of the lower 30 end of the detachable grinding-tool.

As illustrated in the drawings, A is the valve-casing, which may be made of any size and form best suited to the purpose for which 35 it is required. A valve-seat, a, is formed in said casing for receiving a disk-valve.

B is a metallic disk-valve, fitted by a "ground joint" to the seat a in the valve-casing. Said valve is attached, by means of an ordinary 40 yielding joint, to the screw-stem b. A slot, b', or other suitable device, is formed in or on the top of the valve B, for receiving the point of a detachable grinding-tool.

C is an opening formed through the axial 45 line of the screw-stem b to coincide with the center of the valve B, so that a grinding-tool similar to the one shown in Fig. 3 may be thereby guided into the slot b'. The outer end of the opening C is adapted to receive a 50 stopper, which I preferably make in the form of a screw-plug, D, whereby said opening is hermetically sealed to prevent the escape of any steam or water which otherwise might leak therethrough.

The grinding-tool shown in Fig. 3 consists 55 of a cylindrical stem, E, that fits easily in the opening C, and is provided with a flattened end, e; but instead of the latter it may be formed to fit into or onto any device with which the upper part of the valve B is provided for receiving such tool. The said tool may be provided with any kind of a handle that is best suited to imparting to it a rotary motion; but from preference I use it in the form of a bit-stock. 60

To grind the valve B to the valve-seat the plug D is removed, and, after applying any suitable abrading material to the valve, the grinding-tool E is inserted in the opening C until the point E engages in the slot b', then 70 a few rotatory or vibratory movements are imparted to the valve by means of said tool to produce a tight joint between the valve and its seat, and as this operation is performed while all of the working parts are in the positions where they perform their several functions the work will be rapidly accomplished, and with such accuracy as to avoid any liability of the valve to be thrown out of coincidence with its seat, which defect is a frequent occurrence when the valve is ground without such a steadiment. 75

I am aware that globe-valves have heretofore been constructed with a hollow screw-stem containing a secondary stem that extended through the hollow stem and was provided at its lower end with a socket that served as a guide for the valve; but both stems have no connection to the valve for the purpose of lifting it from its seat. Therefore I 85 do not wish to be understood as claiming a hollow screw-stem or the other parts of a valve, as hereinbefore described, otherwise than in the combination specified in the following claim. 90

I claim as my invention—

The combination, with a valve, B, provided with a slot, b', or other similar device for receiving a detachable grinding-tool, of the stem b, jointed to the valve B and provided 100 at its axial center with an opening, C, for the admission of a detachable grinding-tool, as herein described, the opening C being adapted to receive a stopper, D, as and for the purpose herein specified.

Witnesses: WILLIAM GARDNER.
